CLAIM

The ornamental design for an adapter for vial, as shown and described.

DESCRIPTION

Figure 1.1 is a perspective view of an adapter for vial, showing our new design;

Figure 1.2 is a left view thereof;

Figure 1.3 is a right view thereof;

Figure 1.4 is a front view thereof;

Figure 1.5 is a back view thereof;

Figure 1.6 is a top view thereof;

Figure 1.7 is a bottom view thereof; and

(Continued)

Figure 1.8 is a cross-sectional view thereof taken along plane A-A' of Figure 1.6.

1 Claim, 8 Drawing Sheets
